UNITED STATES PATENT OFFICE.

MICHAEL W. FEENEY, OF ROCHESTER, NEW YORK, ASSIGNOR TO ANCHOR COMPANY, OF CHICAGO, ILLINOIS, A CORPORATION OF ILLINOIS.

RAIL ANCHOR.

Application filed March 19, 1921. Serial No. 453,693.

To all whom it may concern:

Be it known that I, MICHAEL W. FEENEY, a citizen of the United States, residing at Rochester, in the county of Monroe and 5 State of New York, have invented new and useful Improvements in Rail Anchors, of which the following is a specification.

This invention relates to rail anchors.

An object of the invention is to provide 10 an efficient, positive tilting rail anchor, which when supported by the rail base will increasingly grip the same as the rail tends to creep.

Another object is to provide an improved 15 anchor which may be readily and firmly applied to a rail.

Another object is to provide a rail anchor which may be readily adjusted and positioned on a rail.

20 Another object is to provide an improved anchor employing adjustable attaching means whereby the anchor may be readily positioned on and rigidly fastened to a rail.

Another object is to provide a simple, 25 lightweight, efficient anchor which may be economically manufactured.

Other objects and advantages will herein-after appear.

The views of the drawings are:

30 Figure 1 is a perspective of the rail anchor with the attaching means therefor separated therefrom.

Figure 2 is an end elevation of the anchor applied to a rail.

35 Figure 3 is a top plan of the anchor applied to a rail.

Figure 4 is a side elevation of the anchor applied to a rail.

The anchor has upper and lower jaws 1 40 and 2, a leg 3 and a foot 4, and a bolt or attacher 5 for attaching the same to the rail base. The jaws, leg and foot of the anchor may be cast integrally from malleable iron or steel, while the attacher may be formed 45 separately from similar material.

The anchor may be applied to the side of the rail with the jaws embracing the rail base flange 6, as shown in Figures 2, 3 and 4, the upper jaw 1 being above, and the 50 lower jaw 2 being below the flange.

The leg 3, extending downwardly from and at an angle to the jaws, is provided with the foot 4 near its lower end for abutting the tie as the rail tends to creep, and thus 55 acting as a fulcrum on which the anchor

may tilt. The engaging surface of the foot 4 is forward of the upper end of the leg 3, so that the upper end is free to move after movement of the lower end, or foot 4, is arrested by engagement thereof with a tie. 60 The anchor is accordingly free to tilt with the foot 4 acting as a fulcrum.

The jaws 1 and 2, and the leg 3 with its foot 4, form the anchor proper, and are arranged to take the stress of the creepage. 65 A reinforcing web 7 extends between the lower jaw 2 and the leg 3. The forward end of the upper jaw 1 and the rear end of the lower jaw 2 may be enlarged so as to give them increased strength where they 70 impinge upon the rail base flange.

The anchor is attached to and maintained in position on the rail base by means of the bolt or attacher 5 having at one end a jaw 8 for engaging the rail base flange 9 and having its other end threaded for receiving a nut. The shank of the bolt extends transversely to the length of the rail at an angle thereto, while the threaded end thereof extends through an aperture in the 80 reinforcing web 7. The threaded end of the bolt 5 is arranged to receive a nut 10 whereby, after the anchor has been applied to the rail and the bolt arranged in the position shown in Figure 2, the nut may be 85 tightened and thus securely fasten the anchor to the rail. A pad 11 may be provided on the web 7 around the aperture therein for insuring a smooth surface against which the nut 10 may be seated; this 90 pad also serves to strengthen the web. The web is further strengthened by a similar pad on the opposite side thereof.

The jaw or hook 8 may be formed by flattening and bending an end of the bolt, thus 95 providing a larger bearing surface where it contacts with the rail base flange 9.

When the rail tends to creep in the direction indicated by the arrow in Figure 4, the bolt 5 causes the anchor to be carried 100 along with the rail until the foot 4 of the depending leg 3 engages a tie. Upon further tendency of the rail to creep, the upper end or jaws of the anchor is moved forward, but the lower end or foot 4 is retarded. The anchor is accordingly tilted on the fulcrum formed by foot 4, so that the forward end of jaw 1 impinges upon the upper surface of the rail base flange 6 and the rear end of jaw 2 impinges upon the lower 110

surface of this rail base flange. The base is thus firmly gripped between the jaws of the anchor. The more the rail tends to creep, the tighter the jaws grip the base.

5 The bolt 5 serves to prevent longitudinal movement of the anchor along the rail, and, therefore, insures positive tilting thereof.

After the jaws have gripped the rail base flange, the attaching means or bolt 5 is relieved of the stress of creepage, which is thereafter borne by the rail base, the jaws and the leg of the anchor. The bolt or attaching means may, therefore, be comparatively small, since it is subjected to very little strain.

Since no preliminary preparation of the rail is necessary when applying and attaching an anchor thereto, the labor and cost of so applying and attaching the anchor are reduced. Furthermore, the position of the anchor with respect to a tie may be very accurately adjusted, since the hook of the bolt may grip the rail base flange 9 at any point along its length, and the bolt may be attached after the anchor has been applied to the rail.

While but one embodiment has been shown and described, it is obvious that the invention contained herein is susceptible of other embodiments and adaptations.

The invention claimed is:

1. A rail anchor comprising a pair of jaws for gripping a rail base flange and having their surfaces of engagement with opposite faces of the rail base extending longitudinally of the rail, a depending leg for engaging a cross-tie to tilt the jaws to cause them to increasingly grip the flange as the rail tends to creep, and means extending under the rail and transversely to the length thereof for engaging the other rail base flange and having less extent longitudinally of the rail than the jaws whereby the anchor is held against displacement and positive tilting of the jaws is insured.

2. A rail anchor comprising a pair of jaws for gripping therebetween a rail base flange, a depending leg to cause the jaws to grip the flange increasingly when the leg abuts a tie as the rail tends to creep, a strengthening web extending between the leg and the jaws, and fastening means extending between the strengthening web and the other rail base flange and having a nut 50 on one end thereof for drawing the jaws into firm engagement with the rail base whereby when the leg abuts a tie the an-

chor is held against displacement and positive tilting of the jaws is insured.

3. A rail anchor comprising a pair of jaws for gripping therebetween a rail base flange, a depending leg to cause the jaws to grip the flange increasingly when the leg abuts a tie as the rail tends to creep, a strengthening web extending between the leg and the jaws, and a fastening rod arranged to extend from the strengthening web under the rail base at an angle thereto and provided with a jaw for engaging the other rail base flange, whereby when the leg abuts a tie the anchor is held against displacement and positive tilting of the anchor jaws is insured when the leg abuts a tie.

4. A rail anchor comprising a pair of jaws for engaging and increasingly gripping a rail base flange when tilted, a depending leg for abutting a tie to tilt the jaws as the rail tends to creep, a strengthening web extending between the leg and the jaws, and an attacher arranged to engage the other rail base flange and extending transversely under the rail at an angle thereto and engaging the strengthening web for holding the anchor in place and positively insuring the tilting of the jaws.

5. A rail anchor comprising a pair of jaws for engaging and increasingly gripping a rail base flange when tilted, a depending leg for abutting a tie to tilt the jaws as the rail tends to creep, a strengthening web extending between the leg and the lower jaw, and an adjustable attacher having a hook for engaging the other rail base flange and arranged to extend transversely to the length of the rail and to engage the strengthening web whereby the anchor is held in place and positive tilting of the jaws is insured.

6. A rail anchor comprising a pair of jaws for engaging and increasingly gripping a rail base flange when tilted, a depending leg for abutting a tie to tilt the jaws as the rail tends to creep, a strengthening web extending between the leg and the jaws, and an attacher arranged to extend through the strengthening web and having at one end a hook for engaging the other rail base flange and having its other end arranged to receive a nut whereby when the leg abuts a tie the anchor is held against displacement and positive tilting of the jaws is insured.

In witness whereof, I have hereunto subscribed my name.

MICHAEL W. FEENEY.
